Geo. B. Selden.

UNITED STATES PATENT OFFICE.

JAMES G. CUTLER, OF ROCHESTER, NEW YORK.

AIR-CUSHION FOR LETTER-BOXES.

SPECIFICATION forming part of Letters Patent No. 381,058, dated April 10, 1888.

Application filed July 8, 1887. Serial No. 243,758. (No model.)

To all whom it may concern:

Be it known that I, JAMES G. CUTLER, of Rochester, Monroe county, New York, have invented certain new and useful Improvements 5 in Air-Cushions for Mail-Chutes, of which the following is a specification, reference being had to the accompanying drawings.

My present invention relates to improvements in air-cushions for letter-boxes, designed 10 especially for use in connection with the mail-chutes or letter-box connections described in my former patents, No. 284,951, September 11, 1883, and No. 336,038, February 9, 1886, but capable of being used in connection with any 15 letter-box in which a cushion is employed to break the force of the fall of articles placed therein.

My invention relates to an improved apparatus for filling or charging the air-cushion, 20 which apparatus is arranged to be operated by the movement of the door of the box when the collector gathers the mail.

My improvements are fully described and 25 illustrated in the following specification and accompanying drawings, the novel features thereof being specified in the claims annexed to the said specification.

My improvements in air-cushions for letter-boxes are illustrated in the accompanying 30 drawings, in which—

Figure 1 is a plan view, the box being indicated in dotted lines. Fig. 2 is a front elevation, showing also a portion of the mail-chute. Fig. 3 is a section on the line xx , Fig. 35 Fig. 4 represents a modification.

In the accompanying drawings representing my improvements, A is a letter-box of any preferred construction, which is provided with the air-cushion B, of rubber or any other suitable material. The box A is provided with the door C, from the lower part of which there projects downward a stud or pin, D, which carries an arm or segment, E, extending under the box, and operating the piston of an 40 air-pump, by means of suitable connections, when it receives motion from the opening or closing of the door C. The arm E is preferably a segment of a circle and moves in guides F, attached to the bottom of the box.

To the inner end of the segment or arm E 50 is pivoted a suitable connection, J, which transmits motion to the piston G of the air-pump.

The cylinder H of the air-pump is secured to the under side of the mail-box, and connected by a suitable tube, L, with the air-cushion inside the box. The piston G is provided with a suitable valve, which opens as the piston moves outward, so as to admit air back of the piston, and which closes as the piston begins its return movement, so that as the door of the box is closed by the collector the air before the piston is driven out through the tube into the air-cushion, so as to inflate the latter or maintain the supply of air therein.

The tube L, connecting the cylinder H and the air-cushion B, is provided with a suitable check-valve to prevent the escape of air from the cushion. The valves are preferably arranged so as to close by gravity, and a cap, N, carrying a stuffing-box through which the piston-rod passes, may be attached to the air-cylinder. A valve opening inward should in this case be applied to the cap.

In order to prevent the escape of air from the cushion during any long period in which the door is not opened, through any accidental leakage through the valves, a cock or valve may be inserted in the pipe L.

In order to provide for adjusting the amount of motion given the piston G by the swinging 50 of the mail-box door, I form on the end of the segment E the slotted arm I, extending radially inward. The end of the connection J can be moved on this arm toward the center of the segment, as shown at J', and secured in 55 place by a suitable clamp or thumb-screw, thereby lessening the throw of the piston, as indicated by the dotted lines G" G'". By this means the amount of air forced into the cushion may be lessened, so as to prevent over-charging when the door is frequently opened, as would be the case where the collections of mail from the box are made frequently.

From the foregoing description the operation of my improved device will be readily 95 understood. When the door of the box is opened, the piston G of the cylinder H is drawn out and the air passes into the cylinder through the valve in the piston, the check-valve in the outlet-tube preventing the air in the cushion from following the piston. As the door closes, the piston is forced in and the air before it raises the check-valve and enters the cushion.

In Fig. 4 I have shown a modification of my

device, in which a flexible bulb, K, is compressed by the closing of the door. A plate is secured to the end of the segment, so as to compress the bulb K against a suitable seat formed for it on the bottom of the mail-box. The bulb is made of rubber or other suitable material, and provided with inlet and outlet valves and connected to the air-cushion, so that the air contained in the bulb may be forced into the cushion when the door of the box is closed.

Any suitable means may be employed for adjusting the amount of compression given the bulb—as, for instance, the device shown in Fig. 4 of the drawings, where the segment is made in two pieces secured together by a thumb-screw, so that the length of the segment is adjustable, and the amount of compression given the bulb thereby may be varied.

It is obvious that various modifications of my device may be substituted for the arrangement herein described—as, for instance, the pump may be arranged to force air into the cushion on the opening of the door; or the connecting-rod J or the piston-rod may be directly attached to the door without the intervention of the quadrant.

If desired, an auxiliary air-pump may be arranged on the apparatus, by which the cushion may be inflated, if it becomes necessary, between the visits of the collector.

By means of my invention the air-cushion in the mail-box, which serves to break the fall of any mail matter or parcels inserted in the mail-chute, is kept continually inflated or distended by the action of the collector in opening or closing the door of the box.

I claim—

1. The combination, with a mail-box provided with an interior air-cushion, of means, substantially as described, for inflating the cushion, operated by the opening or closing of the door of the box, as and for the purposes set forth.

2. The combination, with a mail-box provided with an interior air-cushion and a movable door, of an air-forcing device connected to the air-cushion and arranged to be operated by the movement of the door, substantially as described.

3. The combination, with a mail-box provided with an interior air-cushion and a movable door, of an air-cylinder, H, communicating with the air-cushion and provided with piston G, and suitable connecting mechanism, whereby the movement of the door is transmitted to the piston, substantially as described. 55

4. The combination, with the descending tube of a mail-chute, of the mail-box A, provided with an interior air-cushion and a movable door, and a suitable air-forcing device adapted to inflate the air-cushion and arranged to be operated by the door of the box, substantially as described. 60

5. The combination, with the mail-box A, 65 provided with hinged door B and air-cushion C, of air-pump H, connecting pipe and valve L, and suitable connecting mechanism, whereby the piston of the pump is operated from the door, substantially as described. 70

6. The combination, with the mail-box A, provided with air-cushion B and movable door C, of a suitable air-forcing apparatus connected to the air-cushion, and adjustable connecting mechanism between the door and the said apparatus, whereby the volume of air delivered to the cushion may be varied, substantially as described. 75

7. The combination, with the mail-box A, provided with air-cushion B and door C, of the 80 air-cylinder H, pipe L, piston G, connection J, and segment E, substantially as described.

8. The combination, with the mail-box A, air-cushion B, and door C, of the segment E, having radial extension I, and connection J, adjustable thereon and arranged to communicate motion from the door to an air-forcing apparatus adapted to inflate the air-cushion, substantially as described. 85

9. The combination, with the mail-box A, 90 provided with interior air-cushion, B, and movable door C, of a suitable air-forcing apparatus connected with the air cushion, arranged to be operated by the movement of the door, and located beneath the mail-box, substantially as described. 95
